ALBERT B. BEAN, OF NEW HAVEN, CONNECTICUT.

Letters Patent No. 62,923, dated March 19, 1867.

IMPROVEMENT IN MACHINES FOR MAKING NUTS.

The Schedule referred to in these Letters Patent and making part of the same.

TO ALL WHOM IT MAY CONCERN:

Be it known that I, ALBERT B. BEAN, of New Haven, in the county of New Haven, and State of Connecticut, have invented a new Improvement in Nut Machines; and I do hereby declare the following, when taken in connection with the accompanying drawings, and the letters of reference marked thereon, to be a full, clear, and exact description of the same, and which said drawings constitute part of this specification, and represent, in—

Figure 1, a side view.

Figure 2, a top view.

Figure 3, a longitudinal horizontal central section; and in

Figure 4, a portion of the same section to illustrate the operation of the machine.

This invention relates to an improvement in machines for the manufacture of metal nuts or such as are used for bolts, &c., from hot metal; and that others may be enabled to construct and use my improvement, I will proceed to describe the same as illustrated in the accompanying drawings.

A is the bed-plate, supported upon legs B' or otherwise. B the driving-shaft supported and so as to be revolved freely in bearings C by the application of power to the pulley D. From the said shaft B, power is communicated, to the cam-shaft E through gear-wheels F and G, the said shaft E supported and revolving in bearings H. I is a slide moving freely in guides J, by the action of a cam, K, bearing against the said slide to force it forward, as seen in fig. 3, and returned by the reaction of a spring denoted in broken lines d, fig. 1, or otherwise the said slide I carrying the hollow punch L, which is of the size and form required for the nut to be produced. M is a second slide lying back of the slide I, and moving freely in guides N forward by the action of the cam P, and returned by the reaction of the said cam upon the arm R attached to the said slide. At the forward end of the slide M is the die-holder S, in which is fixed a die, a, (see fig. 5,) adjusted to position by screws b, and through which the hollow punch L freely passes. T is the crowner, of the same size as the punch L, fixed in a holder, U, so as to correspond in position to the punch L, the said holder U being hinged to the frame at f, so that it may be turned to the position denoted in red, fig. 3, for the purpose hereafter shown. In the rear of the holder U is arranged a slide, W, moving freely in guides X forward by the action of the cam Y, and return by the action of the cam l through the rod Z and the lever g, as seen in fig. 3, carrying with it a punch, i, which passes through the crowner T, and corresponding to the hole in the punch L, and of the size required for the piercing of the nut. The said punch i is thus moved from the position in fig. 3, to that denoted in red, fig. 4, and returned, and is adjusted by a set-screw, h.

The operation of my machine is as follows: When in the position denoted in fig. 3, the metal of which the nut is to be formed, after being properly heated, is placed between the punch L and crowner T, as denoted in blue, fig. 3. Power being applied to the machine forces the punch forward, pressing the metal between the two, as denoted in blue, fig. 2; then the slide M advances, the die cutting off the blank and following on to the crowner, as denoted in fig. 4. In this position, and while the punch and die are at rest, the piercing punch i is advanced, forcing the central portion of the metal into the hollow of the punch L, which completes the blank; then by the return of the several parts, the nut is forced from the die and from the piercing punch, so that by no possibility can the nut cling to any of the parts, but must necessarily drop from the machine. A second blank is in like manner introduced, the second piercing following the first into the punch L, from thence passing out through the hollow of the punch or otherwise disposed of.

It is often necessary to repair to a greater or less extent the dies, the crowner, or the punch, and which repair, if it were possible to get at the parts in the machine, could be much better done than to remove them from the machine. To attain this object the holder U is hinged to the frame, as before described; it is secured to the frame by screws n, by the removal of which, and the withdrawal of the piercing punch, the holder may be turned to the position denoted in red, fig. 3, thus enabling the workman to get at the several parts without removal or disarrangement, one great advantage which my improvement has over machines heretofore constructed.

Another advantage arises from the fact that the piercing is done while all the parts except the piercing punch are at rest, whereby any irregularity or defects in the surface of the nut are filled, and the nut comes

from the machine more perfect than can be done in machines which pierce the nut in its earlier stages, or while it is being moved in the die.

Another advantage which my machine has over others, arises from the fact that the thickness of the nut is governed by the movement of the punch L, and as this completes its movement before the die advances, all surplus metal is cut away and does not enter the die, whereas, in other machines the metal is forced into the die before it is compressed, and thus, as the quantity of metal varies, so must the pressure and the strain of the machine more or less increase.

I do not wish to be understood as claiming the forcing of the metal into the body of the nut by the piercing punch, as such is not new; neither do I entirely thus force the metal, only such portions of it as will fill the die.

Having therefore thus fully described my invention, what I do claim as new and useful, and desire to secure by Letters Patent, is—

The crowner T, in combination with the punch L, and die A, and hinged holder U, substantially as and for the purpose set forth.

ALBERT B. BEAN.
